UNITED STATES PATENT OFFICE.

REUBEN SLOTE, OF MOUNT VERNON, NEW YORK, ASSIGNOR TO SLOTE & KLEIN, INC.,
OF NEW YORK, N. Y., A CORPORATION OF NEW YORK.

DESIGN FOR A BELT BUCKLE.

Application filed January 8, 1929. Serial No. 29,538. Term of patent 3½ years.

To all whom it may concern:

Be it known that I, REUBEN SLOTE, a citizen of the United States, residing in the city of Mount Vernon, county of Westchester, State of New York, have invented a new, original, and ornamental Design for a Belt Buckle, of which the following is a specification, reference being had to the accompanying drawing, forming part hereof.

Figure I is a face view of the belt buckle showing my new design.

Figure II is a plan view of the belt buckle of my new design.

I claim:

The ornamental design for a belt buckle, as shown.

REUBEN SLOTE.
